(57) **CLAIM**

The ornamental design of a tablet or mobile device friction/adhesive tilt mechanism, as shown and described.

DESCRIPTION

FIG. 1 is a rear elevational view of a tablet or mobile device friction/adhesive tilt mechanism showing our new design;
FIG. 2 is a bottom plan view thereof;
FIG. 3 is a front elevational view thereof;
FIG. 4 is a left-side elevational view thereof;
FIG. 5 is a right-side elevational view thereof;
FIG. 6 is a perspective view thereof; and,
FIG. 7 is a top plan view thereof.
